CLAIM

The ornamental design for a minizip drive, as shown and described.

DESCRIPTION

FIG. 1 is a top plan view of a minizip drive depicting my new design;

FIG. 2 is a bottom plan view of the embodiment shown in FIG. 1;

FIG. 3 is a first side elevational view of the embodiment shown in FIGS. 1-2;

FIG. 4 is a front elevational view of the embodiment shown in FIGS. 1-3; and,

FIG. 5 is a rear elevational view of the embodiment shown in FIGS. 1-4.

The opposite side is a mirrored image of the first side elevational view.
